UNITED STATES PATENT OFFICE

148,365

DESIGN FOR A HOUSE

Edwin O. Klemm, Saginaw, Mich.

Application July 2, 1946, Serial No. 131,284

Term of patent 14 years

(Cl. D13—1)

To all whom it may concern:

Be it known that I, Edwin O. Klemm, a citizen of the United States, residing at Saginaw, in the county of Saginaw and State of Michigan, have invented a new, original, and ornamental Design for a House, of which the following is a specification, reference being had to the accompanying drawing, forming part thereof, wherein:

I claim:

The ornamental design for a house, substantially as shown.

EDWIN O. KLEMM.
